UNITED STATES PATENT OFFICE.

FREDERICK JIRA, OF SAN FRANCISCO, CALIFORNIA.

AUTOMATIC GUARD AND CIRCUIT-BREAKER.

1,253,832.

Specification of Letters Patent. Patented Jan. 15, 1918.

Application filed August 28, 1916. Serial No. 117,203.

To all whom it may concern:

Be it known that I, FREDERICK JIRA, a citizen of the United States, residing at the city and county of San Francisco and State of California, have invented new and useful Improvements in Automatic Guards and Circuit-Breakers, of which the following is a specification.

My invention relates to elevators, and to means for automatically operating guards which are movable to protect the sidewalk opening when not occupied by the elevator platform, and to cause the guard to be withdrawn, when the opening is closed. It also comprises means by which the movements of the elevator platforms act to operate a circuit breaker, and to arrest the movement of the platform, at either end, of its journey, or in case of an obstruction which might cause an accident, and in details of construction which will be more fully explained by reference to the accompanying drawings in which—

Figure 1 is a front elevation of elevator with platform at bottom of shaft.

Fig. 2 is front elevation of elevator showing automatic safety stop in operation.

Fig. 3 is a side elevation of elevator.

Fig. 4 is a partial elevation of elevator from opposite side to Figs. 1 and 2.

Fig. 5 is a partial plan of elevator.

Fig. 6 is a partial horizontal section through 6—6 of one corner of elevator.

Fig. 7 is a horizontal section through line 7—7 of Fig. 8.

Fig. 8 is an enlarged partial elevation of Fig. 4, showing operation of automatic safety stop on gate.

My invention is here illustrated in connection with a sidewalk elevator in which a platform A is movable between guide posts 2 from a basement to the sidewalk level 3. An opening is made in the sidewalk into which the elevator's platform just fits when at the top of its travel. Doors 4 are hinged to opposite edges of the opening and close to meet on a center line, level with the sidewalk. A rigid segment 5 has its ends fixed to the platform and it arches upward so as to contact with the doors and raise them outwardly about their hinges, as the platform rises, until, when the platform is level with the sidewalk the doors will stand approximately vertical, in which position they are retained by chains 6 and rod 6^a and thus serve as guards to two sides of the opening.

An intermediate side is protected by a guard or gate 7, which is slidable in guides extending downward along the posts 2, and is raised or depressed in unison with the movements of the platform A, as follows:

The platform is suspended and moved by means of ropes 8 passing over suitably disposed pulleys 9 beneath the sidewalk, these ropes being connected with a main hoisting rope 8^a which may be connected with a winding drum and a motor. Guided weights 10 have connections 11^a with yokes 14 which curve around the parts 2 and are connected with slides 15 which are caused to move vertically by guides on the posts 2, as shown in Figs. 3 and 6.

When the platform A is at its lowest point the weights 10 are also down and the gate 7 is up. When the platform rises, attachments carried by it contact with the yokes 14 raising them and the connected weights 10 and at the same time allowing the ropes 11 to move around the pulleys 12. The opposite ends of these ropes are connected with extensions below the gate 7, shown in Fig. 4, and thus allow the gate to descend as the platform goes up, until, when the platform is level with the sidewalk surface, the gate will be at or below that level. When the platform is lowered, a reversal of this operation takes place and the weights 10 act, through the ropes 11 moving around the pulleys 12, to raise the gate to its safety position.

In order to stop the elevator platform when it arrives at either end of its travel, I have shown an electrical switch 16 by which the motor is controlled and means operated by the movements of the platform, to open the motor actuating circuit at the proper times. As here shown, this means includes a vertically slidable rod 17, the lower end of which is guided below the platform and the upper end upon a cross frame timber near the top, as shown in Fig. 3. Connected with the rod 17, near the upper end, is a short bar 19, the upper end of which has a lug 17^a which is adapted to be engaged by the platform as it approaches the upper limit of its travel and it thus acts to push the rod 17 up. Near the lower terminus of the platform travel is another lug 17^a in such position that the platform will contact with it as it approaches the lower end of its travel and pull the rod 17 down. The lower end of the rod has two

2
projecting pins or lugs 18 situated a short distance apart, and one end of a fulcrumed switch lever 16 extends between these lugs which alternately contact with the lever and move it up or down. The opposite end of this lever moves over an arc having switch points 16^a at each end of the path of travel of the arm 16.

The movement of the arm in one direction makes contact with one point which energizes the motor to, through its connections, move the platform in one direction or the other, and when the platform has reached either end of its travel the switch will be automatically disconnected by the action of the lugs 17^a moving the lever 16.

It sometimes happens that, some part of the elevator load, or a person, will be carelessly left to project beyond the edge of the platform and thus cause an accident by crushing between the platform and the side of the opening. In order to prevent this, a bar 20 is supported by hinged links 21 parallel with, and contiguous to, the elevator opening and so near that anything projecting from the platform would raise the bar. The ends of the bar rest upon supports 22 which are electrically connected to maintain the motor circuit, and the bar is held down by a light spring 23, the tension of which will be overcome and the bar lifted by contact of anything projecting from the platform, and the circuit thus broken, and the platform stopped.

Various modifications of this invention may be employed, with the same result, and within the scope of this specification and claims, and I do not waive my title to modifications.

Having thus described my invention, what I claim and desire to secure by Letters Patent is—

1. In a sidewalk elevator, a vertically guided platform, a gate for projection above the sidewalk having downward post extensions, a pulley adjacent each of the latter, cables attached at one end to the lower ends of the post extensions and passing upwardly over the pulleys, vertically guided weights attached at the opposite ends of the cables, and means for lifting the weights arranged thereabove and connected thereto for lifting vertically on the weights, said means having a part normally arranged in the path of

travel of the platform to be engaged thereby for operating said lifting means. 65

2. In a sidewalk elevator, a platform, a vertically movable gate, spaced guide posts for the interposed gate, a pulley on each post, a cable passing about each pulley and connected at one end to the gate, a weight connected to the opposite end of each cable for normally holding the gate operative, a pair of superposed brackets on each post, guide rods connecting the superposed brackets for guiding the weights, a slide member slidably mounted on each guide post, a U-shaped bracket secured to each slide member in straddling relation to the post, one arm of the U-bracket being engageable by the platform for moving the slide member, means connecting the opposite arm to the adjacent weight for lifting the same on movement of the slide member to permit a lowering of the gate. 75

3. In a sidewalk elevator, a platform, a gate, a pair of vertical guides for the gate, each guide having a trackway disposed longitudinally, a slide member movable by the platform on each trackway and having 80 an inwardly extending arm, means connected to the gate for holding the same operative, a connection between the arms and said means for rendering the gate inoperative. 85

4. In a sidewalk elevator, a platform, a gate, a pair of vertical guides for the gate, each guide having an I-sectioned trackway disposed longitudinally thereof, a slide member on each trackway embracing the 90 opposite sides of the web of the latter, a substantially U-shaped bracket for each slide member secured at its base to the latter with its side arms extending on opposite sides of the respective guide, one side arm 95 being engageable by the platform to move the slide member in one direction, and means for rendering the gate operative and connected to the other side arm for moving the respective slide member in the opposite 100 direction.

In testimony whereof I have hereunto set my hand in the presence of two subscribing witnesses.

FREDERICK JIRA.
